UNITED STATES PATENT OFFICE.

FREDERICK A. JOHANKNECHT, OF BIRMINGHAM, ALABAMA.

DESIGN FOR A VEHICLE.

58,490.

Specification for Design.

Patented July 26, 1921.

Application filed February 23, 1921. Serial No. 447,332. Term of patent 14 years.

To all whom it may concern:

Be it known that I, FREDERICK A. JOHANKNECHT, a citizen of the United States, and a resident of Birmingham, in the county of Jefferson and State of Alabama, have invented a new, original, and ornamental Design for Vehicles, of which the following is a specification, reference being had to the accompanying drawing, forming part thereof.

The figure is a side elevation of the vehicle.

I claim:

The ornamental design for a vehicle, as shown.

FREDERICK A. JOHANKNECHT.
